UNITED STATES PATENT OFFICE.

DE WANE B. SMITH, OF UTICA, NEW YORK.

DESIGN FOR A FEED-CUTTER KNIFE.

SPECIFICATION forming part of Design No. 25,777, dated July 14, 1896.

Application filed October 8, 1895. Serial No. 565,077. Term of patent 14 years.

To all whom it may concern:

Be it known that I, DE WANE B. SMITH, of Utica, in the county of Oneida, in the State of New York, have invented a new and useful 5 Design for a Feed-Cutter Knife, of which the following is a specification, reference being had to the accompanying drawings, showing a part thereof.

Figures 1 and 2 are respectively front and 10 rear elevations of a feed-cutter knife embodying my design, and Fig. 3 is an edge view of said feed-cutter knife.

The leading feature of my design consists in a body formed with a contracted substantially horizontal right-hand end and an enlarged opposite end having its lower edge disposed considerably beneath the corresponding edge of the former end; a projection extending from the front face of the 15 right-hand end of the body at the inner side of its outer extremity and formed with a substantially circular perforation; a shank extending downwardly beneath the outer extremity of the right-hand end of the body 20 and having its upper end inclined rearwardly beyond the rear face of the body and its lower end provided with an enlarged extremity and arranged substantially parallel with said rear face, and a handle projecting from 25 the end edge of the enlarged left-hand end of the body and arranged in a plane disposed at substantially right angles with the shank.

A is the body, B the shank, and C the 30 handle.

The body A is formed with a contracted substantially horizontal right-hand end a and an enlarged opposite end a', having its lower edge disposed considerably beneath the corresponding edge of the end a. The central 35 portion a² of the top edge of the body A is disposed in a substantially flat plane. Its extremity a³, forming the top edge of the end a, is depressed and arranged substantially parallel 40 with said central portion, and its opposite extremity a' is curved downwardly. The lower edge a⁵ of the body A extends downwardly in a concave plane from the extremity a and the opposite end edges a⁶ a⁷ of said 45 body are disposed at substantially right angles with its top edge, although the greater portion of the end edge a⁷ extends in compound-curved planes. The outer extremity 50 of the contracted end a inclines rearwardly from its upper edge a⁸, as best seen at Fig.

3, and at the inner side of said outer extremity is a projection a⁹, which extends from the front face of the end a and is formed with a substantially cylindrical aperture a⁹. The shank B extends downwardly from the outer 55 extremity of the end a and its upper end b inclines rearwardly beyond the rear face a¹⁰ of the body A. The lower end b' of the shank B is arranged substantially parallel with the face a¹⁰ and is provided with an enlarged extremity formed with substantially parallel sides b² and a rounding top b³. The lower edge b⁴ of said enlarged extremity is disposed in a plane arranged at substantially right angles with the sides b², and its front 65 and rear faces are formed respectively with angular and circular sockets b⁵ b⁶.

The handle C projects from substantially the central portion of the end edge a⁷ of the body A and is arranged in a plane disposed 75 at substantially right angles with the shank B. The inner end of the handle is substantially flat, and its front face is arranged in substantially the same vertical plane as the corresponding face of the body A, and the outer end c of said handle is formed rounding in cross-section and is curved downwardly.

The front faces of the handle C and the body A are provided with a rib D, having one 85 end extending lengthwise of the longitudinal central portion of said handle from substantially the inner extremity of its outer end c and its opposite end projecting upwardly in a plane arranged substantially concentric 90 with the adjacent portion of the edge a⁵ of the body A and provided at its extremity with a lateral arm d, arranged substantially parallel with the projection a⁸.

My design is very pleasing in appearance 95 and adds greatly to the salability of the feed-cutter knives.

What I claim is—

The design for a feed-cutter knife, substantially as herein shown and described. 100

In testimony whereof I have hereunto signed my name, in the presence of two attesting witnesses, at Syracuse, in the county of Onondaga, in the State of New York, this 25th day of July, 1895.

DE WANE B. SMITH.
